UNITED STATES PATENT OFFICE

121,717

DESIGN FOR A GUARD MEMBER FOR BICYCLE WHEEL HUBS

Walter F. Herold, Easton, Conn., assignor to
The Bassick Company, Bridgeport, Conn., a
corporation of Connecticut

Application April 8, 1940, Serial No. 91,542

Term of patent 14 years

To all whom it may concern:

Be it known that I, Walter F. Herold, a citizen of the United States, residing in Easton, in the county of Fairfield and State of Connecticut, have invented a new, original, and ornamental Design for a Guard Member for Bicycle Wheel Hubs, of which the following is a specification, reference being had to the accompanying drawing, forming part thereof, in which

Fig. 1 is a face view of the guard member showing my new design;

Fig. 2 is a side elevation of the same; and
Fig. 3 is a sectional view of the guard member taken on the line 3—3 of Fig. 1 and looking in the direction of the arrows.

I claim:

The ornamental design for a guard member for bicycle wheel hubs, substantially as shown.

WALTER F. HEROLD.
